Primary Examiner — Patricia Palasik(74) *Attorney, Agent, or Firm* — Marsh Fischmann & Breyfogle LLP; Jonathon A. Szumny(57) **CLAIM**

The ornamental design for a “splitting wedge for log splitter,” as shown and described.

DESCRIPTION

FIG. 1 is a perspective view of a splitting wedge. FIG. 2 is a top view of the splitting wedge of FIG. 1. FIG. 3 is a right side view of the splitting wedge of FIG. 1, the left side being a mirror image thereof.

FIG. 4 is a front view of the splitting wedge of FIG. 1. FIG. 5 is a rear view of the splitting wedge of FIG. 1; and, FIG. 6 is a bottom view of the splitting wedge of FIG. 1. A left side view of the splitting wedge of FIG. 1a has been omitted because it is a mirror image of the right side view of FIG. 1c.
